BACK PROTECTOR

Clara L. Spiess, Philadelphia, Pa.

Application January 9, 1934, Serial No. 705,839

6 Claims. (Cl. 2—43)

My invention relates to new and useful improvements in a back protector to be worn as a garment underneath any of the other garments of the wearer, and has for one of its objects to provide an inexpensive device of this character that will be efficient for the purpose for which it is intended.

Another object of the invention is to so design and shape the back protector that it will readily conform to the contour of the wearer's body, particularly the back, in the region of the kidneys, and the sides.

Another object of this invention is to so construct the back protector that it cannot stretch laterally or become wrinkled while in use.

Another object of the present invention is to provide the protector with stays which will assist in retaining it in proper position on a wearer without the likelihood of the same becoming wrinkled.

Another object of my invention is to provide means for ventilating the protector while in use, some of said means also functioning to hold the stay in place against longitudinal movements.

Another object of the invention is to fashion the protector so as to provide a back portion, side portions and a tail-piece; the latter adapted to cover the buttocks of the wearer and to furnish means for effectively securing the protector in place.

A further object of the invention is to provide a back protector which is sanitary because it is designed for use particularly between garments of wearing apparel, because it is made from fabric which can be washed or otherwise cleansed, and because it is adequately ventilated.

A still further object of the invention is to produce a back protector which will protect certain parts of a wearer's body from the ill effects of the elements and one that will not be habit forming.

With these and other ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawing forming a part of this application, in which:—

Fig. 1 is an outside view of the back protector made in accordance with my invention.

Fig. 2 is an inside view thereof.

Fig. 3 is an enlarged sectional view on the line 3—3 of Fig. 1, and

Fig. 4 is a perspective view, on a reduced scale, illustrating the approximate positions of the parts when the protector is in use.

In carrying out my invention as herein embodied 5 represents the body of the back protector which is to be considered as comprising a back portion 6 and side portions 7. This body is made from suitable material such, for example, 10 as flannel, mole cloth, cotton goods or any textile fabrics or combinations of any number of fabrics.

The body comprises a number of panels 8 extending from the top to the bottom edges and 15 shaped so that said top and bottom edges are longer than the longitudinal center line of the body and these panels are sewn together along their contiguous or meeting edges. This method of forming the foundation of the body provides 20 for a considerable saving in material as the parts can be cut from a large piece of material with very little waste.

On the outside of the body foundation, at each end, is located a reinforcing strip 11, preferably of 25 the same material as the balance of the body, and a similar reinforcing strip 12 is located on the outside of the panels crosswise thereof and in the longitudinal center of the body.

Other reinforcing strips 13, 14, 15 and 16 are placed on the outside of the foundation to cover the meeting edges of adjacent panels or the seams produced by sewing the panels together and said strips are coextensive with said meeting edges or 30 seams.

The reinforcing strips 13, 14, 15 and 16 form 35 pockets 17, one of which is plainly shown in Fig. 3, above and below the longitudinal center reinforcing strip 12. In each pocket is placed a bone, metal or other stay 18. It will be noted that the 40 stays are above and below the longitudinal center of the protector and while they will prevent the formation of wrinkles in the protector they do not interfere with the free movements of the wearer's body.

In order to ventilate the protector, I fix a plurality of eyelets 19 in the body so that they pass through the material and said eyelets are preferably located at some of the thickest parts of the body, particularly in the regions of the reinforcing strips 11, 13, 14, 15 and 16. The eyelets project through said reinforcing strips as well as the 45 foundation of the protector.

The eyelets in the reinforcing strips 13, 14, 15 and 16 are located so that there is one just be- 50 55

yond, but in close proximity to, each end of a stay 18 and therefore besides functioning as ventilating means also act as retainers to hold the stays in place in the pockets.

- 5 Securing straps 29 are attached to the body and by preference there are two of such straps at each end of the body and companion straps are to be adjustably connected by tying them together or by the use of suitable fastenings 21.
- 10 These fastenings may be any well known devices, such as belt buckles, clasps, hooks and eyes and snap fasteners, the latter being shown for purposes of illustration. Where the fastenings are of the type consisting of companion elements, one 15 element of each is carried by one strap and the other element of each is carried by the coacting strap as shown. By mounting a number of the elements on each strap adjustments are provided for as will be obvious.
- 20 The securing straps 20 are to be produced from non-elastic or elastic material or a combination of such materials.

The top and bottom edges of the body are to be finished with a binding 22 of the same material as the balance of the body or it may be some other material and can be in the form of tape or otherwise.

Depending from the lower edge of the body intermediate the ends thereof is a tail-piece 23 which is approximately the same width as the back portion 6 of the protector body or the back panel. Said tail-piece may be an integral part of the back portion of the protector or of said back panel although I have found that by making the same as a separate section, the goods can be cut to better advantage for the elimination of waste to thereby reduce the cost of manufacture.

When the tail-piece is produced as a separate section, it is sewn to the lower edge of the body and the binding 22 extends around the outer edge thereof. A reinforcing strip 24 is disposed on the outside of the protector over the meeting edges of the body and tail-piece. The several parts of the article are sewn together as shown by stitches 25.

While the protector can be placed next to the person of the wearer it is particularly adapted to be worn between garments of ordinary wearing apparel, as between an outer shirt and the vest or coat of male attire.

In putting on the protector it is placed across the back with the back portion of said protector in the region of the wearer's kidneys. The side portions are then drawn against the sides of the wearer and the securing straps fastened together in proper adjustment in front of the wearer's body.

By using this back protector the portions of the wearer's body covered by it will be adequately protected from cold and wind, and therefore such device is particularly adapted for use by persons that have to remain outside for long periods of time, such as officers of the law, motormen, operators of different types of vehicles, salesmen, agents and the like.

When the tail-piece is used it will cover the buttocks or that part of the person's body below the middle of the back. As the article is only a protection against cold and penetrating winds it is not habit forming and can be discarded whenever desired or whenever it is not required.

Of course I do not wish to be limited to the exact details of construction herein shown and described as these may be varied within the scope

of the appended claims without departing from the spirit of my invention.

Having thus fully described my invention, what I claim as new and useful is:—

1. A back protector comprising a body including a plurality of sectional panels secured together along their meeting edges, a reinforcing strip extending along the longitudinal center of the body, other reinforcing strips covering one side of the meeting edges of the panels and projecting above and below the first mentioned reinforcing strip, each of said second mentioned reinforcing strips providing pockets both above and below the said first mentioned reinforcing strip, stays in said pockets, eyelets projecting through the body within the boundaries of the second named reinforcing strips to ventilate the protector, said eyelets being positioned beyond the ends of the stays to also function as retainers for said stays, additional reinforcing strips at the ends of the body, other eyelets projecting through the body within the boundaries of the last mentioned reinforcing strips for ventilation purposes, and securing straps fixed to the ends of the body.

2. The structure set forth in claim 1, in combination with a tail-piece depending from the lower edge of the body intermediate its ends.

3. A back protector comprising a body including a number of panels sewn together and so shaped that the upper and lower edges of said body are longer than the longitudinal center thereof whereby the protector will conform to the body of a wearer, each panel consisting of a pair of similar sections sewn together, a reinforcing strip extending along the longitudinal center of the body and covering one side of the seams produced by sewing the panel sections to one another, other reinforcing strips extending along the meeting edges of the panels coextensive therewith and covering the seams produced by sewing said panels together, said second mentioned strips providing pockets above and below the longitudinal reinforcing strip, stays in said pockets, additional reinforcing strips extending along the ends of the body, eyelets projecting through the body within the boundaries of the second and third mentioned reinforcing strips for ventilating the protector and the eyelets in the second mentioned reinforcing strips being positioned beyond the ends of the stays to retain the latter in their pockets, a tail-piece attached to the lower edge of the body intermediate the ends of said body and depending therefrom, a reinforcing strip extending along the meeting edges of the body and tail-piece, a binding extending along the upper and lower edges of the body and about the outer edge of the tail-piece, securing straps fixed to the ends of the body, and means for fastening companion straps together in any selected adjustment.

4. In a device of the kind described, a body, reinforcing strips extending across said body from the top to the bottom edge thereof, another reinforcing strip extending along the longitudinal center of the body, eyelets projecting through the body within the boundaries of said first named reinforcing strips for ventilation purposes and defining limits of pockets in said first named reinforcing strips above and below the longitudinal reinforcing strip, and stays in said pockets.

5. A back protector comprising a body including a number of panels sewn together and so shaped that the upper and lower edges of said

body are longer than the longitudinal center thereof whereby the protector will conform to the body of a wearer, each panel consisting of a pair of similar sections sewn together, a reinforcing strip extending along the longitudinal center of the body and covering one side of the seams produced by sewing the panel sections to one another, other reinforcing strips extending along the meeting edges of the panels coextensive therewith and covering the seams produced by sewing said panels together, said second mentioned strips providing pockets above and below

the longitudinal reinforcing strip, stays in said pockets, additional reinforcing strips extending along the ends of the body, and straps at the ends of the body.

6. The structure in claim 5, in combination with a tail-piece attached to the lower edge of the body intermediate its ends and depending therefrom, and a reinforcing strip extending along the meeting edges of said body and tail-piece.
